UNITED STATES PATENT OFFICE.

WILLIAM LEONARD, OF NEW YORK, N. Y., ASSIGNEE TO E. W. BLISS COMPANY, OF NEW YORK, NEW YORK, A CORPORATION OF WEST VIRGINIA.

GYROSCOPIC STEERING MECHANISM.

1,204,853.

Specification of Letters Patent. Patented Nov. 14, 1916.

Application filed November 18, 1915. Serial No. 61,735.

To all whom it may concern:

Be it known that L. W. Leonard Durbin, a citizen of the United States of America, residing in the borough of Brooklyn, county of Kings, city and State of New York, have invented certain new and useful Improvements in Gyroscopic Steering Mechanism, of which the following is a specification.

This invention relates to gyroscopic mechanisms for controlling the steering of torpedoes or other craft. In such mechanisms the gyroscope is locked just during the spinning up of the torpedo and at the end of the spinning operation is unlocked and set free. The present invention relates to the means for holding and unlocking the gyroscope.

The invention will be described with reference to a gyroscope which is spun by compressed air as used in the Bliss-Leonard torpedo. It is, however, applicable to gyroscopes having other means for spinning.

Figure 1 of the accompanying drawings is a vertical mid-section of the gyroscope of an automobile torpedo, the plane of the section being front-and-a-half. Fig. 2 is a perspective view of the locking bolt.

Referring to the drawing, A is the fly-wheel of the gyroscope, B the inner gimbal thereof which stands normally horizontal, C the outer gimbal thereof which is in a vertical plane, D as a whole the supporting means for the gyroscope, and E the fixed frame. The gyroscope support D is shown as comprising a cylindrical shell e, a top plate b having at e the upper ball bearing on the vertical axis of the gyroscope and a lower head d having at e the lower ball bearing on such axis. The fly-wheel axis has a pinion f which is engaged by the pinion g on the spindle h of a small turbine i which is driven by oblique jets of air from a nozzle j in order to spin up the fly-wheel. At the end of the spinning-up operation a sliding sleeve k which carries the shaft h is unlocked and moves suddenly to the left in Fig. 1, thereby displacing the pinion g and turbine to the positions shown in dotted lines. The same movement unlocks the gyroscope which previously has been held locked by a bolt g, the spherical end of which enters a socket l in the gimbal B coincident with the fly-wheel axis. The bolt is unlocked by means of a bracket or forked arm m which projects forwardly from the

slide k and works in a slot n in the bolt, striking the end of this slot and drawing back the bolt at the end of its movement. Heretofore the bolt has been guided at opposite ends and engaged only by the forked arm m which retains the bolt in its locked and unlocked positions in the respective extreme positions of the slide k. It has been found in some cases however that the gyroscope was unlocked prematurely, whereby its direction was deranged, with the result that the torpedo would steer a different course from that aimed. The present invention provides an improved construction which avoids this disadvantage. 79

According to the present invention the locking bolt is pressed into action by a spring which holds it against premature movement during the retracting movement of the slide and until the arm m positively withdraws it. Also, instead of guiding the forked arm on the bolt, a fixed guide is provided against which the arm slides, and which also serves to guide the bolt. This fixed guide is shown as a pin or stud G 80 which is fixed in the frame E, standing in line with the fly-wheel axis when in the spinning position. The bolt F is made tubular and slides over the pin G. Its upper half is cut away at n so as to expose the pin, 85 and the forked arm m enters this cut-out portion and embraces the pin so as to be guided thereon. Beneath the bolt is another fixed pin H which serves as the guide for a helical spring J which presses the bolt forward by engaging a downwardly projecting ear p formed on the bolt and which is perforated to slide along the pin H.

In the locking and unlocking movements of the slide k it is operated by the usual 95 forked arm K fixed on a rock shaft L which is connected to the usual mechanism for imparting the unlocking movement. In this movement the forked arm K engaging the slide k is liable to exert a side thrust 100 which tends to press the arm m to one side and this tendency is thought to have had the effect heretofore of prematurely moving the locking bolt. Hence the lateral thrust of the fork m is now taken up against the immoveable pin G and cannot affect the bolt. The bolt is held in its locked position by the spring J during the unlocking movement of the slide k and until the forked arm m abuts against the end of the notch n, and 110

thereby carries the bolt bodily with it. Hence the bolt is not unlocked until the very end of the movement of the slide. It results that the unlocking of the gyroscope before 5 the pinion *g* has ceased to impel the pinion *f* is prevented.

The invention is not limited to the particular structure or details shown which may be varied according to the skill and judgment of the designer and which will require variation to adapt the invention to other types of gyroscopic mechanism.

What I claim is:—

1. In a gyroscopic steering mechanism, 15 the combination with a gyroscope of unlocking means comprising a bolt engaging the inner ring of the gyroscope, a spring pressing said bolt to the locked position, and unlocking means comprising a reciprocating 20 slide moving parallel to the bolt and having an arm adapted to engage said bolt toward the end of its unlocking movement, and thereupon to withdraw it against the stress of its spring.
2. In a gyroscopic steering mechanism, the 25 combination with the gyroscope and spinning-up mechanism therefor, of locking

means comprising a bolt engaging the gyroscope, said bolt having a tubular body and cut away to form opposite shoulders, a guiding pin within the tubular bolt, and unlocking means comprising a slide movable parallel with the bolt and having an arm moving between said shoulders and engaging and guided by said pin.

3. In gyroscopic steering mechanism, the combination with a gyroscope and spinning-up mechanism, the latter comprising a slide adapted to execute an unlocking movement, and an arm projecting from said slide, locking means comprising a bolt engaging the gyroscope, a spring pressing said bolt to the locked position, a fixed pin guiding the movements of the bolt, the bolt having a notch exposing said pin, and said arm entering 45 said notch and engaging said pin to be guided thereby.

In witness whereof I have hereunto signed my name in the presence of two subscribing witnesses.

WILLIAM DIETER.
